UNITED STATES PATENT OFFICE.

ERICK W. PETTERSSON, OF JAMESTOWN, NEW YORK, ASSIGNOR TO WILLIAM LEWIS,
OF UTICA, NEW YORK.

SPRING BED OR SEAT.

1,312,870.

Specification of Letters Patent.

Patented Aug. 12, 1919.

Application filed July 9, 1914. Serial No. 849,921.

To all whom it may concern:

Be it known that I, ERICK W. PETTERSSON, a subject of the King of Sweden, residing at the city of Jamestown, in the county of 5 Chautauqua and State of New York, have invented certain new and useful Improvements in Spring Beds or Seats, of which the following, taken in connection with the accompanying drawings, is a specification.

10 The invention relates to spring beds and similar constructions; and the object of the improvement is to provide a coil spring for the outer edges of a box seat or box bed single or double cone spring, or for supporting 15 the edges of woven wire mattresses which support spaced binding wires on said springs to assist in holding the clothing or mattress or other covering in place; and second, to provide an improved support for a 20 spring mattress on the bedstead which is easy of adjustment thereon and detachment therefrom; and third, to provide an improved head or foot board construction; and the improvement consists of the novel features and combinations hereinafter set forth 25 and claimed.

In the drawings, Figure 1 is a perspective view of the corner of a woven wire mattress showing the improved support therefor 30 on the bedstead and the edge supporting spring and spaced binding wires to hold the mattress and bed clothes in place.

Fig. 2 is a perspective view of the corner of a box bed or seat spring showing the extensions on the tops of the springs and the 35 spaced binding wires attached thereto.

Fig. 3 is a sectional view at line X X in Fig. 1, showing the preferred manner of attaching the edge supporting spring for the 40 woven wire mattress to the bed rail or support and showing the spring top extension, with the binding wires in section.

Fig. 4 is a sectional view of the edge of a 45 box bed or seat spring having single cone springs.

Fig. 5 is a perspective view of my improved hook for the attachment of the bed to the head or foot board; and Fig. 6 is a perspective view of the end of the bed rail 50 or spring bed frame formed to engage said hooked support on the foot or head board.

Fig. 7 is an elevation of the head or foot board of a bedstead showing the improved panel construction; and Fig. 8 is a sectional view of the panel showing the manner of

double covering with cane or cloth the panels for the bedstead; and Fig. 9 is a similar sectional view showing the single covering for the panels, one side being left uncovered; and Fig. 10 is a perspective view of 60 the lower end of one of the corner posts and cross bars and panel work in the head or foot board of the bedstead, the panel work being shown in section, and showing the manner in which it is fitted into the bedstead.

Like numerals of reference refer to corresponding parts in the several views.

The numeral 10 designates a double coil spring, and the numeral 11 a single coil 70 spring. It will be apparent that my improved top construction may be used upon either form of spring.

The numeral 12 designates the upwardly projecting loop or bend in one side of the 75 top coil of the springs 10 or 11 for attaching the binding wires 13 and 14 thereto so that the top binding wire 14 is a spaced distance above the lower binding wire 13 and both are firmly attached to yet resiliently 80 held in position upon said spring. The attachment is preferably made for the binding wires 13 and 14 to the upward projection 12 by wire wraps or metal strips. The upward projection of the top coil of the spring for 85 the corner spring is given an angular bend, as shown at 15 in Fig. 2, and the binding wires 13 and 14 are bent to correspond with the angular bend in the upward projection 15. 90

The improved woven wire mattress 16 is provided with an end cross strip 17 which is bent upward at 18 in Fig. 1, and the binding wires 13 and 14 are attached thereto to support the ends of said wires in binding the 95 edges of woven wire mattresses. Coil springs are placed at spaced distances along the edges of the woven wire mattress 16 to support said edges and also to support the spaced binding wires 13 and 14 in the same 100 manner as upon a box bed or seat spring.

The lower ends of the springs 10 or 11 are supported in the usual form in box bed or seat springs, as shown in Figs. 2 and 4. The woven wire mattress 16 has an end bar 19 105 connected to the cross strip 17 by means of coil springs 20 at spaced distances. The crosswise end bar 19 is attached to the ends of the side rails 21 of the bed. The cross bar 19 is made wedge shape to fit within a 110

hook 22 which is attached to the bed post so that the end of the cross bar 19 may fit any desired position as to sidewise adjustment within the opening in the hook 22.

5 In order to surely lock the cross bar 19 within the hook 22, a hook plate 23 is attached to the top of the cross bar 19 at each end and has a beveled lower end 24 which fits over the opposite beveled upper end 25 of the hook 22. It is now apparent that the cross rail 19 may be quickly and easily slipped within the hook 22, the hook 23 automatically engaging the beveled surface of the upper end. These two hooks react on 10 one another so that the cross bar 19 does not wedge too tightly within the hook 22, yet the bar is held firmly in line until it is desired to separate the parts.

The lower ends of the double coil springs 20 10, which are preferably used for the edges of the woven wire mattress 16, extend down upon the opposite sides of the side rail 21, as shown at 26 and 27 in Fig. 3, and where the side rail 21 is in the form of an angle iron 25 the inward downwardly projecting portion of the spring 10 may be bent up against the under side of the bed rail 21, thereby holding the base of said edge spring firmly upon the bed rail 21, yet permitting its full resiliency to the upper portion of the spring.

It is apparent that my upwardly bent loop 12 or 15 may be provided on any form of coil spring in which it is desired to have an upwardly projecting binding wire around 30 the outer edge to provide a confining flange around said edge for the mattress, bed clothes or other covering.

The head and foot board of the bedstead is an improvement upon the construction shown 40 in my Letters Patent No. 1,017,793, February 20, 1912, as follows: The corner posts 28 are grooved lengthwise on their inner edges as shown at 29 to receive therein the edge of the single or double faced panel 30 or 31, 45 the single faced panel 30 being used preferably for head boards which usually extend against the wall and the double panel construction 31 is used for foot boards which more generally extend out into the room and 50 have both sides exposed. The panels 30 and 31 are constructed with projecting edges 32 which extend into the groove 29, which groove extends down the lateral sides of the posts 28 and across the underside of the top 55 molding 33, the top molding 33 being fitted to the top of the posts 28 with dowel pins 34.

A covering 35 which may be of fancy cloth, leather, cane or other material is provided for the panels 30 and 31 in the following manner: The material is placed over the sides of the panel and extends into a groove 36, which groove extends entirely around the edge of the panel, and a wire 37 is then bound over the material 35 into said groove 60 36, thereby stretching the covering 35 firmly

upon the panel 31 and holding the edges or ends of the same firmly in place.

It is apparent that a simple and beautiful covering may thus be given to the panel which is as durable as the material used. A 70 cross bar 38 is provided from one post 28 to the other immediately below the panel 30 or 31 which supports the panel in place, and the panel may be extended below the first cross bar to a second single or double cross 75 bar 39, as shown in Fig. 10, thereby strengthening the construction of the foot or head board and more firmly holding the panels 30 or 31. It is also obvious that the simple method of attaching the covering 35 may be 80 attained on different articles of furniture and not depart from my invention.

I claim as new:

1. In a seat or bed spring, suitably supported coil springs, binding wires around the 85 tops of the outer row of coil springs, and an upwardly projecting loop or bend in the top coil of each of said outer coil springs to support one of said binding wires a spaced distance apart from the other and form a 90 flange.

2. In a seat or bed spring, suitably supported coil springs, an upwardly projecting flange around the outer edges of said seat or bed spring consisting of an upward projection of the top coil of the outer row of springs, and spaced binding wires attached to said upward projections of said top coils at their base and upper extremity to hold said binding wires a spaced distance apart 95 and form a flange.

3. In a seat or bed spring, coil springs suitably arranged and supported to form a bed or seat, upwardly projecting loops on 100 said coil springs along the sides and at the corners of said bed or seat, said upwardly projecting loops of the corner springs given an angular bend to form the corner turn, and binding wires attached to said upwardly projecting loops of said side and corner 110 springs and bent to conform thereto a spaced distance apart to form a flange around the outer edges of said seat or bed springs.

4. A seat or bed spring comprising the combination with a mattress of coil spring 115 supports for the edge of said mattress, an upwardly projecting loop on each of said coil spring supports, binding wires attached to said projecting loops a spaced distance apart, and suitable supports for the ends of 120 said binding wires to form a side flange for said woven wire mattress.

5. A seat or bed spring comprising the combination with a woven wire mattress of 125 coil spring supports for the edge of said woven wire, an upwardly projecting loop on said coil spring supports, binding wires attached to said projecting loop a spaced distance apart, suitable supports for the ends of said binding wires to form a side flange 130

- for said woven wire, and downwardly projecting loops from the bottom coil of said coil spring to engage the support for said coil spring along the edge of said woven wire 5 mattress.
6. In a spring bed, a set of helical springs along one side thereof and supported from the bottom, the upper ends of the springs being provided with upward extensions 10 forming loops or bends with wide bases and projecting above the main bodies of the springs, and a guard rail attached to the high points of the loops or bends.
7. In a spring bed, opposite sets of helical 15 springs arranged along the sides of the bed and supported from the bottom, the upper ends of the springs of each set being provided with upward extensions forming loops or bends with wide bases and projecting 20 above the main bodies of the spring near the outer edges thereof, and guard rails mounted upon said loops or bends.
8. A bed spring comprising supporting means, spiral springs carried thereby, and a 25 side-guard located along each outer longitudinal row of spiral springs to project above the same and consisting of a series of upright members located between the ends of the spring, and members connecting said 30 upright members, each of said upstanding members consisting of a continuation of a spiral spring with its free end hooked into a coil of said spring.
9. A bed spring comprising supporting 35 means, spiral springs carried thereby, a side guard located along each outer longitudinal row of spiral springs to project above the same for preventing the flattening, spread-
- ing and sagging of a stuffed mattress over the edge of the spring, and means for maintaining the lower edges of the side guards in 40 substantial juxtaposition to the spiral springs.
10. A bed spring comprising supporting means, spiral springs carried thereby, a side-guard located along each outer longitudinal 45 row of spiral springs to project above the same, and means connecting the guard with said springs for preventing the flattening, spreading and sagging of a stuffed mattress 50 over the edge of the spring.
11. A bed spring comprising supporting means, a series of spiral springs carried thereby, brackets at each side extending above said springs, a guard member connected to said brackets for preventing a 55 stuffed mattress from flattening, spreading and sagging over the lengthwise edge of the spring, and means connecting said guard member with the outer row of springs. 60
12. A bed spring comprising supporting means, spiral springs carried thereby, a side-guard located along and supported by each outer row of spiral springs to project above the same, and means for placing the guard under tension lengthwise thereof for preventing a stuffed mattress from flattening, spreading and sagging over the lengthwise 65 edge of the spring.
- In testimony whereof I have affixed my 70 signature in the presence of two witnesses.
- ERICK W. PETTERSSON.
